UNITED STATES PATENT OFFICE.

WILLIAM P. MAINGAULT, OF TACOMA, WASHINGTON.

AMMONIA COMPRESSOR.

Application filed May 15, 1924. Serial No. 713,523.

To all whom it may concern:

Be it known that I, WILLIAM P. MAINGAULT, a citizen of the United States, residing at Tacoma, in the county of Pierce and State of Washington, have invented new and useful Improvements in Ammonia Compressors, of which the following is a specification.

This invention relates to ammonia compressors of the splash type with ported suction, and particularly to the construction 10 of the cylinder wall.

The primary object of the invention is to overcome the numerous disadvantages incident to constructing a ported compressor 15 for ammonia or other gas or air and particularly the inaccuracies found in molded constructions wherein the port between the gas chamber and the compressor cylinder is cast in the metal and requiring the use of 20 a boring tool, which runs to a certain degree or cannot be regularly controlled, to produce the resultant formation that is economically practicable.

A further object of the invention is to 25 adopt a construction which will avoid a loss in spoiled castings in endeavoring to form the port through molding means and during the subsequent treatment of such castings by machine shop work and the use of a boring tool, which is always liable to run irregularly in passing a cast port and resulting 30 in the complete loss of the pieces of work when thus spoiled.

A still further object of the invention is 35 to generally improve the construction of compressors for ammonia, gas or air by a reliable formation of the port, or means of communication between the gas chamber and the compressing cylinder, and also to decrease the expense of production by reducing 40 to a minimum injured or spoiled work that usually results from the methods commonly practiced in forming the port or communicating opening between the compressing cylinder and the gas chamber.

The present invention consists essentially 45 in casting the entire body of a compressor for ammonia, air or other gas in one piece in such manner that the outside and inside 50 walls of the cylinder are primarily continuous, and wherein no ports at the lower and upper portions exist. The cylinder is then bored true, and after the latter operation a cutting tool is used, preferably in a boring bar, and the inside cylinder wall is cut 55 through into the gas chamber, this cut being

continued fully around the cylinder and as narrow as practicable, to permit the cylinder to fill with gas from the gas chamber. The remaining necessary port or ports are 60 formed after the cylinder is bored. The piston rings are formed very much wider than the port, or communicating opening between the cylinder and the gas chamber, so as to readily travel over the said port or opening 65 without the least liability of the said rings dropping into the port. It is also proposed to include the same essential features of invention in ammonia, air or gas compressors 70 of the single or double cylinder type, the double cylinder organization having each cylinder thereof in full communication through the port formed therein, as above specified, and also in communication with a gas chamber which surrounds the cylinders 75 and extends between the latter.

The invention also consists in the details of construction and arrangement of the several parts which will be more fully herein-after described and claimed.

In the drawings:

Fig. 1 is a transverse vertical section of a compressor body embodying the features of the invention and showing a piston therein and a part of the mechanism for operating 85 the latter, together with the upper compressing chamber and the discharge means therefor;

Fig. 2 is a similar transverse vertical section of the improved structure taken in a 90 plane at right angles to that shown by Fig. 1;

Fig. 3 is a horizontal section on the line 3—3, Fig. 2;

Fig. 4 is a horizontal section on the line 95 4—4, Fig. 2;

Fig. 5 is a transverse vertical section through a double cylinder organization embodying the same features of the invention;

Fig. 6 is a horizontal section on the line 100 6—6, Fig. 5; and

Fig. 7 is a horizontal section on the line 105 7—7, Fig. 5.

The numeral 5 generally refers to the body of the improved compressor, which comprises outer and inner walls 6 and 7 of integral formation. The inner surrounding wall 7 defines a piston chamber 8, which opens at its upper terminal into a receiving or compression chamber 9, surrounded by an 110 annular water chamber 10 with upper and lower inlets and outlets 11 and 12 for cir-

culation of water in the chamber, thus providing a practical form of water jacket for obvious purposes. On the top of the body 5 over the chamber 9 a head or cap 13 is 5 removably secured. Within the piston chamber 8 the usual form of piston 14 is mounted to reciprocate, and as one form of operating means has a piston rod 15 connected thereto and to the crank 16 of a shaft 10 17 mounted in suitable bearings in the lower part of the body and adapted to be actuated by any preferred form of motive mechanism. Primarily the cylinder or piston chamber 8 is bored, and around this cylinder 15 between the walls 6 and 7, in the single form of the compressor as shown by Fig. 1, an annular gas chamber 18 is formed, the entire body being cast and the chamber 18 as well as the water space or chamber 10 20 being produced by cores sustained in operative position during the molding operation by any suitable means and in accordance with well known practices in the molding art. After the piston chamber or cylinder 25 8 has been bored, communication is established with the gas chamber 18 by a suitable boring tool, preferably carried by a boring bar, said communication being through the medium of a comparatively narrow slot 30 or port 19, which opens into the upper part of the chamber 18 and is of less vertical extent than the width of the piston rings 20, so that the latter in traveling over the inner terminal of the slot or port 19 will 35 not spring into the said slot but readily pass the same without the least obstruction to the regular reciprocation of the piston 14. The gas chamber is connected by suction ports 21 with any suitable gas or air 40 supply source, and these ports as well as the lower drain ports are formed in the wall 6 and preferably screw-threaded, for receiving correspondingly threaded ends of connecting pipes illustrated in part by dotted lines. The advantage of this construction 45 is that the slot or port 19 may be readily and accurately produced without the least injury to the casting as a whole and in contradistinction to the modes of construction heretofore usually adopted and which 50 consist in molding the means of communication between the cylinder 8 and the gas chamber 18. It will be understood that the pipe connections to both sets of ports 21 and 22 will be also provided with suitable 55 valves and the receiving or compression chamber 9 into which the cylinder or piston chamber 8 opens is formed with diametrically opposed ports 23 for discharge purposes, and the pipe connections thereto are 60 also illustrated in dotted lines in Fig. 2 and may be provided with suitable valves. As shown by Fig. 3, the gas chamber 18 completely surrounds the cylinder or piston 65 chamber 8 and the gas therefrom flows

through the communicating slot or port 19 into the said cylinder or piston chamber 8 equally and regularly and rapidly charges the space above the upper end of the piston when the latter is at the lower limit of its 70 stroke, and on the return or upward stroke the gas or air is compressed into the receiving or compression chamber 9 and from the latter is discharged or conducted away from the compressor as desired. The gas 75 chamber as constructed and confined between the inner and outer walls 6 and 7 permits a storage of a considerable quantity of the gas, to ensure a quick and rapid supply to the piston chamber 8 through the 80 narrow slot or port 19. This deep chamber, which jackets the piston chamber 8, also serves as a trap to keep the liquid from going direct to the piston chamber. Many 85 accidents have been caused by liquid passing direct from the gas chamber into the piston chamber or cylinder in ammonia compressors, but in accordance with the present construction, as above noted, ammonia liquid will be trapped in the deep 90 chamber 18 and subsequently pass off as a gas. The relative positions of the ports 11 and 23, respectively opening into the water space or chamber 10 and the receiving 95 or compression chamber 9, are clearly 100 illustrated by Fig. 4, and it will be seen that the said ports 23 are formed in a thickened portion of the upper wall of the body slightly above the plane of the lowermost 105 portions of the ports 11, and there is therefore no interference in the construction of these two sets of ports, or the ports 23 are formed in a solid wall at diametrically opposite portions of the upper part of the body 5. It will also be understood at the time the cylinder or piston chamber 8 is bored that the receiving or compression chamber 9 may be completed and the latter is of greater diameter than the piston chamber or cylinder. 110

In the form of the improved device as shown by Figs. 5, 6 and 7 two cylinders are shown associated in a single organization and each provided with a piston, the first piston and its cylinder together with the compression chamber thereover being designated by the same reference characters as in Fig. 1, and likewise the means for operating this piston. The second cylinder 24 has a piston 25 therein with an operating connection 26 attached to the lower end and the outer wall 6 in the single cylinder formation as heretofore described is increased in diameter to embrace both cylinders. Also, the gas chamber 18^a is increased in diameter and surrounds both cylinders 8 and 24 and also has communication with an open space 25^a in the center between the two cylinders. The cylinder 8 has the same form of slot or port 19 opening into the gas chamber 18^a 130

and the cylinder or piston chamber 24 has a similar slot 19^a opening also into the said gas chamber. The upper and lower suction and drain ports 21 and 22 are formed in the outer diametrically enlarged wall 6 and function in a manner similar to the ports bearing like numerals and illustrated by Figs. 1 to 4, inclusive. In addition to the receiving and compression chamber 9 there is a second receiving and compression chamber 9^a having a head or cap 13^a thereover similar to the head or cap 13, and the water chamber is increased by an intermediate water space 10^a, which is in communication 10 with the outer space 10 corresponding to those shown by Figs. 1, 2 and 4. The ports 21 and 22 will also be provided in this double construction with suitable pipe connections 26 and 27, as shown by dotted lines, and 15 these pipe connections may obviously be provided with suitable valves. Likewise, the upper water space or jacket has upper and lower ports 28 and 29 for circulating purposes, said ports being adapted to have suitable pipe connections as also indicated in 20 dotted lines in Fig. 5. The receiving or compressing chambers 9 and 9^a will both be provided with discharge outlets 23^a and 24^a with the same function or operation as 25 hereinbefore explained in connection with the single cylinder form of the compressor.

From the foregoing it will be seen that the operation is quite simple, and the stroke of one or more cylinder and piston organizations 30 sets up a suction which will draw the gas first into the annular gas chamber 18 or the chamber 18^a with the intermediate communicating space 25, and as each piston descends to the lower limit of its stroke, 35 the port or slot openings 19 or 19^a are cleared and the gas flows into the cylinder

or cylinders in which the piston or pistons operate and by the latter is forced upwardly into the single or double receiving or compressing chambers. The formation of the 40 ports or slots providing the means of communication between the gas chamber and the cylinder or cylinders insures an equal and rapid charging of the cylinder or cylinders, and on the downstroke of the piston or 45 pistons, vacuum resistance is destroyed and the piston or pistons are permitted to travel downwardly without restriction by reason of the removal therefrom of the vacuum load. 50

What is claimed as new is:

An ammonia compressor of the class specified, comprising a body cast in one piece of material without joints and having outside and inside spaced annular walls, the inner wall providing a piston chamber and the 55 space between the two walls providing a deep annular gas-receiving chamber, the inner wall enclosing the piston chamber extending practically the full length of the gas chamber and having at the upper limit 60 of the latter chamber a continuous horizontally disposed narrow slot to produce an unobstructed passage between the interior of the piston chamber and the annular gas chamber, the outside wall having ports 65 at the lower termination of the annular gas chamber for drainage purposes and also similar ports near the top limit of the gas chamber and below the said narrow slot for gas supply, and a piston mounted to 70 reciprocate in the piston chamber and pass over the said narrow slot during its reciprocating operation.

In testimony whereof I have hereunto set my hand.

WILLIAM P. MAINGAULT.
